LABORATORY GAS BURNER AND VALVE
OPERATORLeon Riebman and Samuel Lambert,
Philadelphia, Pa.

Application September 16, 1949, Serial No. 116,058

2 Claims. (Cl. 158—111)

1

Our invention relates to gas burners and relates particularly to a single tube burner.

Heretofore, single-tube burners have been manufactured employing a hand-operated valve for regulating the burner flame. When such burners are used in certain manufacturing processes, particularly in the manufacture of molds and artificial dentures, the burners are used frequently but intermittently. It is necessary for the operator to manually light the flame and turn the gas on and off each time the burner is used. If allowed to operate continuously, the burners generate a large amount of heat which makes the air uncomfortable for the workers. Also, this practice wastes gas, and imposes a heavy load on the air conditioning system.

An object of our invention is to provide a laboratory burner which is particularly suitable for intermittent use.

Another object of our invention is to provide a burner of the character described which maintains a tiny pilot flame during the idle period, and which may be turned up as long as necessary by a touch of the finger, or which may be locked in the full flame position for extended periods of time.

A further object of our invention is to provide a burner of the character described which, when released, will automatically turn itself off.

Other objects of our invention are to provide an improved device of the character described, that is easily and economically produced, which is sturdy in construction, and which is highly efficient in operation.

With the above and related objects in view, our invention consists in the details of construction and combination of parts, as will be more fully understood from the following description, when read in conjunction with the accompanying drawing in which:

Fig. 1 is a side elevational view of the burner, part of the interior of which is illustrated in phantom outline.

Fig. 2 is a fragmentary diagrammatic view of the burner in the "off" position.

Fig. 3 is a fragmentary diagrammatic view of the burner in the "on-releasable" position.

Fig. 4 is a fragmentary diagrammatic view of the burner in the "on-locked" position.

Referring now to the drawing, wherein similar reference characters designate similar parts, we show a burner generally designated as A.

The burner A comprises a base 10 adapted to be screwed to the work bench. The base supports a socket 12, the wall of which is laterally drilled

10 to admit a gas tube 14. This tube carries a collar 16 at the free end, over which is slipped the hose from the gas supply (not shown).

5 A nipple 18 threads into the socket 12 and carries at its upper end the valve body 18. The barrel 20 screws into the upper end of the valve body.

The valve body 18 is provided with a vertically-extending gas passage 22, and is horizontally drilled to admit the valve-rod 24. A pilot tube 26 of narrow bore enters the valve body below the rod 24 so that the lower end 28 communicates with the gas passage 22, while the upper end 30 of the pilot tube is fastened adjacent to the burner mouth 32 by a wire clip 34. An air regulating sleeve 36 is supported upon the barrel 20 which is laterally pierced with air holes (not shown).

15 The horizontally extending valve rod 24 has an integral collar 38 which bears against the valve body. The valve rod is secured to the body by an end bolt 40 and a spring washer 42. The rod is transversely drilled to form a gas passageway 44 so that when the passageway is aligned with the vertical body passage 22, the gas passes freely therethrough. The free end of valve rod 24 carries a handle 45 whereby the rod may be rotated by the finger to regulate the flame.

20 A short horizontal pin 46 projects from the collar 38 into an arcuate recess 48 in the valve body. When the rod is rotated to the "on" position (clockwise as seen in Figs. 3 and 4), the pin 46 encounters a spring-pressed ball detent 50 housed in the valve body adjacent the arcuate recess 48.

25 A torsion spring 52 has one end secured in a collar 54 on the valve rod 24, and has its other end fastened to the valve body at a point 56. This spring urges the valve rod 24 counterclockwise, thereby tending to turn the burner off, as in Fig. 2. In this position the pin 46 is arrested by the upper end 58 of the recess 48. Since pilot tube 26 communicates with the gas passage 22 below the valve rod, a small quantity of gas flows through the pilot tube at all times, to supply a tiny flame 60. When the valve handle is depressed by the finger, as shown in Fig. 3, additional gas flows through the barrel and is ignited by the pilot flame, to form a large flame 62.

30 If the burner is to be used for a long period of time, the handle is pressed further down until the pin overrides the detent 50 and abuts the lower end 64 of the recess 48 (as shown in Fig. 4). In this position, the ball detent 50 locks the valve rod in the "on" position, and the operator may re-

move his finger and the burner continues to operate with a full flame. To turn the burner off, the operator merely pulls the lever up, again overriding the detent 50.

Of course, for protracted heating there is no advantage in using such a burner over a conventional burner, but for intermittent use our burner saves gas, is more convenient to use, and does not heat the surroundings objectionably.

Although our invention has been described in considerable detail, such description is intended as being illustrative rather than limiting, since the invention may be variously embodied, and the scope of the invention is to be determined as claimed.

We claim as our invention:

1. A laboratory gas burner having a base, a hollow socket on said base, a gas valve body supported by said socket, a barrel supported at one end of said valve body and in communication therewith, a valve disposed within the interior of said valve body to control the supply of gas to said barrel, a pilot tube having one end adjacent the free end of said barrel and having its other end in constant communication with the interior of said valve body upstream with respect to said valve, means for supplying gas to the interior of said socket, a torsion spring, said valve being urged by said torsion spring to a closed position, and a spring-pressed ball detent carried by said valve body, said detent being adapted to maintain said valve in fully open position against the action of said torsion spring.

2. A laboratory gas burner having a base, a hollow socket on said base, a gas valve body supported by said socket, a valve disposed within the interior of said body and in communication therewith, a finger operated handle to actuate said valve to control the supply of gas to said barrel, a barrel supported at one end of said valve body, a pilot tube having one end adjacent the free end of said barrel and having its other end in constant communication with the interior of said valve body upstream with respect to said valve, means for supplying gas to the interior of said socket, a torsion spring, said valve being urged by said spring to a closed position, and a spring-pressed ball detent carried by said valve body adapted to maintain said valve in fully open position against the action of said torsion spring.
